UNITED STATES PATENT OFFICE.

WILLIAM FRANCIS SMITH, OF BROOKLYN, NEW YORK, ASSIGNOR, BY MESNE ASSIGNMENTS, TO WESTERN ELECTRIC COMPANY, INCORPORATED, A CORPORATION OF NEW YORK.

MANUFACTURE OF ELECTRIC CABLES.

1,223,434.

Specification of Letters Patent.

Patented Apr. 24, 1917.

Application filed May 23, 1914. Serial No. 840,582.

To all whom it may concern:

Be it known that I, WILLIAM FRANCIS SMITH, a citizen of the United States, residing at Brooklyn, in the county of Kings 5 and State of New York, have invented a certain new and useful Improvement in the Manufacture of Electric Cables, of which the following is a full, clear, concise, and exact description.

10 This invention relates to the manufacture of electric cables, and more particularly to the manufacture of pairs of insulated conductors for use in electric cables.

15 The object of this invention is the production of an efficient electric cable of improved and uniform electrical characteristics.

20 The process embodying this invention is an improvement over a process described in Patent No. 1,124,249, issued to Gustavus A. Anderegg, on January 12, 1915. Recent investigations have shown that in addition to the troubles mentioned in the Anderegg patent, there are numerous others which also 25 have a deleterious effect upon the uniformity and degree of the electrical characteristics of electric cables.

It is a fact that in the coils of wire of 30 commercial form there appear various irregularities in the hardness of the wire. These irregularities of hardness have been found to be deleterious in the finished electric cable as evidenced by the variations in the separation of the two wires which form 35 a twisted pair, by the difference in length of the two wires forming a pair, and by variations in the helices in the conductors of the pair.

40 In accordance with the processes of forming twisted pairs of insulated conductors heretofore used there have resulted twisted pairs in which irregular helices appeared in the conductors of any pair and in which there were differences in the lengths of the 45 two conductors of any pair. When such pairs have been used in electric cables, the above mentioned irregular helices and the different lengths of the conductors have had a marked deleterious effect upon the electrical 50 characteristics of the cables.

In order to overcome the deleterious effects just mentioned, this invention provides for the forming of the insulated conductors into helices of the same pitch, and

for the equalizing of the length of the two 55 conductors forming a pair.

This invention will be more fully understood by referring to the drawings showing one embodiment thereof and wherein,—

Figure 1 illustrates apparatus for straightening and for insulating a conductor; 60

Fig. 2 illustrates apparatus for equalizing the length of two conductors, for forming the insulated conductors into helices of the same pitch and for twisting the conductors together; and 65

Fig. 3 is a view of part of the apparatus for equalizing the length of the conductors.

As shown in the drawings, the apparatus for straightening the conductors may conveniently be a wire straightener 4, which 70 consists of two sets of rollers 5 and 6 rotatably mounted on a frame 7. The apparatus for applying uniform insulation to the straightened conductor may be an insulating head 10. This insulating head consists of a plate 11 and a hollow spindle 12 mounted thereon. As the conductor passes through the spindle 12, the insulating head is rotated by any suitable means, as a belt 75 and pulley shown at 13, and insulating tape 14 from a pad of tape 15 is guided on to the conductor by means of a guide 16 mounted on the plate 11, a guide 17 supported on the spindle 12, and the upper 80 portion of the spindle 12. The insulating tape 14 is formed on the conductor in spiral convolutions. A uniform diameter over the insulated conductor is maintained and a definite amount of insulation per unit 85 length of conductor is applied by maintaining a definite relation between the speed of the conductor and the speed of rotation of the insulating head, combined with the use of an insulating head which definitely 90 centers the conductor within the insulating tape, such an insulating head being shown in my copending application, Serial No. 793,129 filed October 3, 1913. The insulating head described in application Ser. No. 100 793,129 consists of a plate having a hollow spindle and guides for the insulating tape 95 mounted thereon.

Suitable mechanism for twisting the insulated conductors together may consist of a 105 revolving shaft 20 carrying a bar 21. Yokes 22, in which spools 23 containing insulated conductors are supported, are mounted on

the ends of the bar 21. The twisting mechanism may be rotated by means of a pulley 24 and a belt 25.

- Apparatus for equalizing the length of the 5 insulated conductors may consist of a frame 30 mounted on top of the shaft 20 and yokes 22. In the frame are mounted a plurality of rollers 31, over which are passed endless belts 32, which, at points upon opposite sides 10 of the frame 30, are forced together by means of spring pressed shoes 33 slidably mounted on the frame 30. As the conductors are passed through the equalizing apparatus, each is gripped by the two endless belts 32, 15 32 due to the action of the spring pressed shoes 33, 33. The gripping of the conductors by the belts causes the travel thereof to be equal to that of the conductors, assuming the tension on the shoes to be adjusted 20 properly. If, therefore, one conductor passes between the belts at a certain rate of speed, the belts will travel at the same rate and since the other conductor is gripped by the same belts, it must necessarily travel at 25 the same rate of speed as the belts and the first mentioned conductor. Consequently, since the speed of the two conductors is equalized, the length of the conductors forming a pair must necessarily be equal.
- 30 The means for forming the insulated conductors into helices of the same pitch may be a rod 40 provided with a plurality of grooves 41 and supported in the top of the frame 30. A detailed description of the apparatus for 35 equalizing the length of the conductors, and of the means for forming the insulated conductors into helices of the same pitch is to be found in Patent No. 1,104,078 issued to me on July 21, 1914.
- 40 The wire 42, which is to form the conductor, is passed from a coil 43, through the device 4 which straightens the conductor. The conductor is then passed through the insulating head 10, which applies thereto a defi-

nite amount of insulation per unit length of 45 conductor. Consequently there results an insulated conductor having uniform diameter and in which the conductor is definitely centered within the insulation. The insulated conductor is wound onto reels 23, which are 50 placed in the yokes 22 of the twisting mechanism. The insulated conductor from each reel 23 is fed up between the endless belts 32 and into the grooves of the rod 40. As the twisting mechanism is rotated, the insulated conductors are drawn forward and engaged by the endless belts 32, which equalize the speed thereof, thereby equalizing the length of the conductors. The insulated 55 conductors, in passing through the grooves 41, of the rod 40, are formed into helices 60 of the same pitch. The rotation of the whole mechanism causes the conductors to be twisted together.

What is claimed is:

65

1. The method of forming a twisted pair of insulated conductors which consists in covering each conductor with insulation, separately forming the insulated conductors into helices of the same pitch, and then 70 bringing the helically formed insulated conductors together to make a twisted pair.

2. The method of forming a twisted pair of insulated conductors which consists in covering each conductor with insulation, 75 feeding the insulated conductors forward at the same speed, separately forming the insulated conductors into helices of the same pitch, and then bringing the helically formed insulated conductors together to make a 80 twisted pair.

In witness whereof, I hereunto subscribe my name this 20th day of May, A. D. 1914.

WILLIAM FRANCIS SMITH.
